UNITED STATES PATENT OFFICE.

GUSTAF L. KOLBERG, OF MILWAUKEE, WISCONSIN, ASSIGNOR TO ALLIS-CHALMERS
MANUFACTURING COMPANY, OF MILWAUKEE, WISCONSIN, A CORPORATION OF
DELAWARE.

PUMP.

Application filed August 29, 1921. Serial No. 496,204.

To all whom it may concern:

Be it known that GUSTAF L. KOLBERG, a citizen of the United States, residing at Milwaukee, in the county of Milwaukee and 5 State of Wisconsin, has invented a certain new and useful Improvement in Pumps, of which the following is a specification.

This invention relates to pumps.

Synchronous alternating current motors 10 have been applied for the purpose of driving pumps but one of the difficulties encountered is that it is not possible to vary the discharge capacity of the pump for the reason that the speed of the synchronous motor 15 cannot be varied as it depends on the frequency of the alternating current. It is accordingly a general object of this invention, to provide simple and efficient means whereby the delivered capacity of a pump may be 20 varied. It is, further, an object of this invention to provide a synchronous-motor-driven pump unit, or a pump unit driven by a motor the speed of which cannot be varied, but in which the delivered capacity 25 may be varied. Other objects will appear hereinafter as a description of the invention proceeds.

The novel features of the invention will appear from this specification and the accompanying drawings forming a part thereof and showing one embodiment of said invention and all these novel features are intended to be pointed out in the claims.

In the drawings, Fig. 1 is a plan view of a 35 pump unit embodying the features of the invention;

Fig. 2 is a side elevation of the pump unit shown in Fig. 1;

Fig. 3 is a vertical sectional view of one 40 of the cylinders of the pump unit shown in Figs. 1 and 2.

The pump unit is shown in the drawings as comprising a synchronous motor 1 driv- 45 ingly connected in any suitable manner to a pair of double acting plungers 2, 3. The number of these plungers is not material. Plunger 2 has associated therewith a pair of cylinders 4, 5 and plunger 3 has similarly associated therewith a pair of cylinders 6, 7. 50 The pairs of cylinders 4, 5 and 6, 7 are here shown as respectively mounted on hollow bases 8, 9 connected by means of a common suction pipe 10 in turn connected to the main suction pipe 11. A pipe 12 is here

shown as providing a common discharge for 55 cylinders 4, 5 by connecting the discharge end of these cylinders. The discharge ends of cylinders 6, 7 are similarly connected by means of pipe 13. A pipe connection 14 is here shown as connected at the respective 60 ends thereof to the discharge ends of cylinders 4, 6 whereby the discharge from all cylinders 4, 5, 6, 7 may reach a main discharge pipe 15. The discharge pipe 15 may be provided with a check valve 16. 65 The pipe connection 14 may have connected therewith a pipe 17 leading to the suction or sump of the pump unit and a valve 18 may be provided in the pipe 17.

Referring now to Fig. 3 in which cylinder 70 4 shown in vertical section, this cylinder is here shown as provided with a suction valve 19 and a discharge valve 20 of any suitable type. A by-pass 21 is provided whereby the cylinder may be connected to its discharge. 75 The by-pass is here shown as connected to the cylinder through the passage 22 and to the discharge through the passage 23. The by-pass is provided with a valve 24 by means of which it may be closed at will. By refer- 80 ence to Figs. 1 and 2 it will be seen that each of the remaining cylinders 5, 6, 7 may be similarly provided with by-pass connections 25, 26, 27 respectively having valves 28, 29, 30. 85

The operation of the pump unit is as follows:

In starting the unit it is preferable to open the valve 18 so as to unload the cylinders and permit discharge into the suction. 90 All of the by-pass valves may also be open during the starting period. When the valve 18 and all of the by-pass valves have been closed the pump unit will deliver its full capacity with the synchronous motor 1 running under normal conditions. If it is now desired to decrease the discharge capacity, one of the by-pass valves 24, for example, may be opened. Under these conditions, assuming plunger 2 to be entering cylinder 5, 95 the suction valve of cylinder 5 will be closed and the discharge valve open. The water or other fluid discharged from cylinder 5 will pass to the discharge and through pipe 12 and an equal quantity of water will enter 100 cylinder 4 through by-pass 21, the suction and discharge valves of cylinder 4 being closed. It will be noted that on this stroke

no water is pumped into the main discharge pipe 15. On the other stroke, when the plunger 2 enters cylinder 4, water will be discharged through by-pass 21 into the discharge and this water will pass into main discharge pipe 15 inasmuch as no water can enter cylinder 5 from the discharge because the discharge valves of said cylinder will be closed. During this stroke, however, 10 water is drawn into cylinder 5 through the suction valve thereof by the action of the plunger. It will thus be noted that the by-pass associated with a given cylinder must be large enough to pass the capacity of the 15 cylinder associated with said given cylinder.

If it is desired to still further reduce the discharge capacity of the pump unit any desired additional number of the by-pass valves 28, 29, 30 may be opened.

20 It should be understood that it is not desired to limit the invention claimed to the exact details of construction shown and described, for obvious modifications will occur to one skilled in the art.

25 It is claimed and desired to secure by Letters Patent:

1. A pump unit including a plurality of cylinders and associated plungers, a motor constrained to operate at a constant speed irrespective of load drivingly connected to said plungers, and means whereby said pump unit may be caused to deliver the capacity of all or any desired number of said cylinders without changing the speed of 35 said motor.

2. A pump unit including a plurality of cylinders and associated plungers, a motor constrained to operate at a constant speed irrespective of load drivingly connected to 40 said plungers, and means including a by-pass between each cylinder and the discharge thereof whereby said pump unit may be caused to deliver the capacity of all or any desired number of said cylinders without changing the speed of said motor.

45 3. In a pump, a double acting plunger, a pair of cylinders for said plunger, a com-

mon discharge for said cylinders, a set of discharge and suction valves for each cylinder, and a closeable by-pass between one of said cylinders and the discharge thereof 50 of said cylinders and the discharge thereof said by-pass being large enough to pass the capacity of the other of said cylinders at maximum discharge rate.

4. In combination, a motor constrained to 55 operate at a constant speed irrespective of load, a double acting plunger drivingly connected to said motor, a pair of cylinders for said plunger, a common discharge for said cylinders, a set of discharge and suction 60 valves for each cylinder, and a closeable by-pass between one of said cylinders and the discharge thereof.

5. In combination, a motor constrained to 65 operate at a constant speed irrespective of load, a double acting plunger drivingly connected to said motor, a pair of cylinders for said plunger, a common discharge for said cylinders, a set of discharge and suction 70 valves for each cylinder, and a closeable by-pass between each of said cylinders and the discharge thereof.

6. In combination, a motor constrained to 75 operate at a constant speed irrespective of load, a plurality of double acting plungers drivingly connected to said motor, a pair of cylinders for each plunger, a common discharge for each pair of cylinders, a set of discharge and suction valves for each cylinder and a closeable by-pass between a desired 80 number of said cylinders and the discharge thereof.

7. In combination, a motor constrained to 85 operate at a constant speed irrespective of load, a plurality of double acting plungers drivingly connected to said motor, a pair of cylinders for each plunger, a common discharge for each pair of cylinders, a set of discharge and suction valves for each cylinder and a closeable by-pass between each 90 cylinder and the discharge thereof.

In testimony whereof, the signature of the inventor is affixed hereto.

GUSTAF L. KOLLBERG.
